(57) CLAIM

The ornamental design for a water cycling platform as shown and described.

DESCRIPTION

FIG. 1 is a top perspective view of a water cycling platform showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is an enlarged detail view taken from portion 9 of FIG. 1;

FIG. 10 is an enlarged detail view taken from portion 10 of FIG. 2; and,

FIG. 11 is an enlarged detail view taken from portion 11 of FIG. 6.

In FIGS. 1, 2, 6 and 9-11, the broken lines represent enlarged sectional designations that form no part of the claim.
